UNITED STATES PATENT OFFICE

JOHN NELSON BANKS, OF WEST WYCOMBE, ENGLAND, ASSIGNOR TO LINOTYPE AND MACHINERY LIMITED, OF LONDON, ENGLAND

TYPE BED OF PRINTING MACHINES

Application filed November 16, 1928, Serial No. 319,858, and in Great Britain December 2, 1927.

This invention relates to the type-beds of bed-and-cylinder printing machines, and has for its object to provide an improved construction of such beds particularly adapted 5 for carrying two type formes, one near each end of the bed or on respectively opposite sides of the transverse centre of the bed.

The improved construction of bed is especially useful in connection with perfector 10 and two-colour machines where the bed cooperates with impression cylinders, disposed approximately centrally of the machine, for printing, in the case of a perfector machine, an impression from one forme on one side 15 of a sheet, and from the other forme on the opposite side of the same sheet. In machines of this kind as at present in use, only one half of the bed is accessible at any one time for the locking up of the respective 20 forme, when the bed is at one end of its reciprocation, the other half of the bed being at that time located mainly beneath the printing cylinders. Consequently, when one 25 forme has been placed in position on the bed, the latter must be moved to the opposite end of its reciprocation so that it may be exposed at the opposite side of the printing cylinders for the locking up of the second forme. This involves loss of time in preparing 30 the press for a run, which the present invention proposes to obviate by providing for both halves of the bed to be accessible simultaneously.

To this end, according to the present invention, the bed is divisible into two readily 35 detachable portions, which can be independently moved to opposite sides of the printing cylinders, and means are provided for rigidly locking together the two portions of the bed, as well as for ensuring rigid engagement 40 of one of the bed portions with the rack hanger attached to the other bed-portion.

The invention will now be described by 45 reference to the accompanying drawings which, as an example, illustrate one constructional form thereof.

In these drawings:—

Figure 1 is an elevation of sufficient of a 50 printing machine, as viewed from the feeder

side, to show the embodiment therein of the present improvements, the two portions of the type-bed being here shown separated from each other;

Figure 2 is a side elevation showing the 55 type-bed portions in working relation;

Figure 3 is a plan of Figure 2;

Figure 4 is a transverse section of the type-bed, and

Figures 5 and 6 are sections taken respectively on the lines 5—5 and 6—6 of Figure 3 drawn to a larger scale.

1 represents one of the two side frames, viz: that of the feeder side of the machine, and 2, 2^a the two printing cylinders mounted 65 therein.

The machine frame, as ordinarily, is provided with tracks or ways supporting rollers whereon the tracks or rails 3 of the type-bed travel in the ordinary well-known manner; 70 the ways and rollers are not shown in the drawings as they are not necessary to an understanding of the invention.

Instead of the type-bed being, as ordinarily, formed of two permanently connected portions, it is, in accordance with the present invention formed in two readily separable portions 4, 4^a adapted to be rigidly connected together at their meeting edges.

For ensuring accurate register and engagement between the two bed portions 4, 4^a, these latter are provided with inter-engaging rails or members 6, 7, which, when said portions are in working relation are locked together by conically seated bolts or dowels 8.

The inter-engaging rails 6, 7, are bolted to the respective bed portions 4, 4^a, as shown best in Figure 6. The rail 6 secured to the bed portion 4 by bolts 9, is formed with recesses 6^a, (Figure 3), for receiving lugs 7^a integral with the rail 7 which is secured to the bed portion 4^a by bolts 10.

Beneath the rail 7 and rigidly secured to the bed portion 4^a by bolts 11 is a bar 12, 95 having lugs 13 housed in recesses formed in the under side of the rail 6, said lugs being threaded for receiving the lower ends of the bolts 8, as shown best in Figure 5.

Holes in the lugs 7^a co-axial with those 100

in the lugs 13, receive with an accurate fit, the upper cylindrical parts of the bolts or dowels 8, while the conical portions of said bolts below these cylindrical parts, nest firmly in correspondingly coned holes in the rail 6. The bolts 8, at their upper ends, terminate in square heads 8^a with which, keys or spanners can be engaged for turning said bolts when it is required to disconnect or 10 connect the two bed portions 4, 4^a.

The rails 6, 7, are provided respectively with upwardly projecting bars 6^b, 7^b, for the locking up of the forms on the respective type-bed portions 4, 4^a.

15 The rack hanger 14 is of substantially the usual form and is permanently attached to the bed portion 4, while the bed portion 4^a is readily detachable from the said rack hanger and is provided with means where- 20 by, when the two bed portions are secured together by the bolts 8, it is accurately clamped to said rack hanger. In the example illustrated, these means consist of three dogs 15 which are rigidly bolted to the 25 underside of the bed portion 4^a, and as shown in Figure 2, have inclined surfaces or jaws 16 adapted to engage with correspondingly inclined surfaces formed on the rack hanger.

30 When, after the removal of the bolts or dowels 8, the two bed portions 4, 4^a, are moved apart, the dogs 15 separate from the engaging parts of the rack hanger 14, and when the two said portions are next 35 brought together, the said dogs firmly engage with the rack hanger, so that, after uniting the bed portions together by the bolts or dowels 8, the machine can be operated as though the bed were in one indi- 40 visible whole.

Having described my invention, I declare that what I claim and desire to secure by Letters Patent is:—

1. In a printing machine, the combina- 45 tion with a type-bed formed of separate portions, of means adapted to secure said portions together with a capacity for their ready disconnection to enable them when so disconnected, to be moved horizontally one 50 away from the other.

2. In a printing machine, the combina- 55 tion with a type-bed formed of separate portions, of means adapted to secure said portions together with a capacity for their ready disconnection to enable them when so disconnected, to be moved horizontally one 60 away from the other, and registering means on the meeting edges of the bed portions 65 mutually engaging with each other to ensure accurate positioning and attachment one relatively to another.

3. In a printing machine, the combina- 70 tion with a type-bed formed of separate portions, of interengaging lugs and recesses of 75 the respective bed portions, and bolts re-

movable from the top of the type-bed, having threaded parts engaging one of the bed portions and conical parts engaging the adjacent bed portion.

4. In a printing machine, the combina- 70 tion with a type-bed formed of separate portions, of means adapted to secure said portions together with a capacity for their ready disconnection to enable them when so disconnected, to be moved horizontally one 75 away from the other, rails independent of the respective bed portions, securing devices permanently attaching the rails to the meeting edges of adjacent bed portions, and forme locking up bars integral with the said 80 rails and projecting upwards beyond the upper face of the bed portions.

5. In a printing machine, the combination with a type-bed formed of separate portions, of interengaging lugs and recesses of the 85 respective bed portions, bolts removable from the top of the type-bed, having threaded parts engaging one of the bed portions and conical parts engaging the adjacent bed portion, rails independent of the respective 90 bed portions, securing devices permanently attaching the rails to the meeting edges of adjacent bed portions, and forme locking up bars integral with the said rails and projecting upwards beyond the upper face of 95 the bed portions.

6. In a printing machine, the combina- 100 tion with a type-bed formed of separate portions, of interengaging lugs and recesses of the respective bed portions, bolts removable from the top of the type-bed, having threaded parts engaging one of the bed portions and conical parts engaging the adjacent bed portion, a rack hanger per- 105 manently attached to one of the bed portions, and attaching means on an adjacent bed portion admitting this last named bed portion being readily connected to and disconnected from the hanger.

7. In a printing machine, the combina- 110 tion with a type-bed formed of separate portions, of means adapted to secure said portions together with a capacity for their ready disconnection to enable them when so disconnected, to be moved horizontally one 115 away from the other, rails independent of the respective bed portions, securing devices permanently attaching the rails to the meeting edges of adjacent bed portions, forme locking up bars integral with the said rails 120 and projecting upwards beyond the upper face of the bed portions, a rack hanger per- 125 manently attached to one of the bed portions, and attaching means on an adjacent bed portion admitting this last named bed portion being readily connected to and disconnected from the hanger.

In witness whereof I have affixed my signature hereto.

JOHN NELSON BANKS. 130
